UNITED STATES PATENT OFFICE.

JOSEPH H. ROACH, OF PHILADELPHIA, PENNSYLVANIA.

FURNACE.

1,346,464.

Specification of Letters Patent. Patented July 13, 1920.

Application filed November 27, 1917. Serial No. 204,245.

To all whom it may concern:

Be it known that I, JOSEPH H. ROACH, a citizen of the United States, residing at Philadelphia, Philadelphia county, and State of Pennsylvania, have invented and discovered certain new and useful Improvements in Furnaces, of which the following is a specification.

My said invention relates to underfeed stoker and forced draft furnaces and to the grate bars therefor *per se*, and consists in the combinations and arrangements of elements hereinafter described and particularly set forth in the accompanying claims.

The invention has for its purpose to provide a grate bar of the stepped type, formed trough-shaped, or inverted U-shaped, in cross section and having internal fins, or flanged portions, reinforcing the stepped members whereby to furnish supports for the steps on which the coal rests, and for the further purpose of increasing radiation, or carrying off the heat, which is greatest at these places in the fire place. Also a grate bar in which the chamber is formed into two separate air spaces having a constricted communicating passageway disposed to direct the air blast from one of said spaces, which is at a higher pressure, to that portion of the other chamber which is at a lower pressure and thereby to add slightly more pressure to the air issuing from the twy whole at which the greatest combustion takes place.

A further purpose is to provide a furnace structure having independently controlled forced draft members below the grate, communicating respectively with separate air spaces formed in the grate bars, to the end that either or both of the air spaces in said grate bars will receive the forced draft from one only, or both of the forced draft chambers.

Another object of the invention consists in providing a channeled or chambered grate bar having a dividing web forming two separate air spaces and which web is constructed in a manner that will allow the air space on one side of the web to receive a small portion of the air delivered to the space on the other side of the web and thereby permit a much lower static pressure to be carried under certain portions of

the grate and thus conserve the life of the furnace structure and increase its efficiency.

The invention is disclosed by way of 55 illustration in the accompanying drawings wherein:

Figure 1 is a longitudinal view of one part of the grate bar,

Fig. 2, a transverse sectional view of Fig. 60 1 taken on the line 2—2 thereof,

Fig. 3, a similar view taken on the line 3—3 on Fig. 1,

Fig. 4, a sectional view of a detail taken on the line 4—4 on Fig. 1, 65

Fig. 5 is a transverse sectional view taken through a portion of an underfeed stoker furnace,

Fig. 6, a longitudinal view of one part of a modified form of grate bar, 70

Fig. 7, a transverse sectional view taken on the line 8—8 of Fig. 6, and

Fig. 8 is a similar view to Fig. 7 showing the grate bar constructed each in one piece.

Referring to the construction in further 75 detail and wherein like reference characters indicate corresponding parts in the different views shown, the grate bar consists of a hollow structure formed on two similar parts 25, and assembled in a longitudinal 80 plane as shown, although it will be understood, of course that the grate bar is constructed with a plurality of steps 26, respectively spaced in a manner to form twy whole openings 27, and the several twy openings of each grate bar are disposed substantially horizontal to direct the forced draft from the air chambers beneath the grate on to the fuel bed supported by the respective steps after the usual manner. 90

A plurality of fins or web portions 28 are formed integrally with each half of the grate bar and immediately beneath and in supporting relation to the step portions thereof for the purpose of furnishing a substantial support to the steps on which the coal rests, and more particularly for the purpose of carrying off the heat which is greatest at these places in the fuel bed. 95

Each bar of the grate is further provided 100 with a transverse web portion or baffle 29 that is disposed near to and diagonally of the notch 18 formed on the lower edge of the grate bar and said notches are adapted

to be engaged and operated by the oscillating shaft 15 of the stoker mechanism, (see Fig. 3). The dividing web or baffle 29 provides a duct or constricted passage 30 giving inter-communication between the two air chambers into which the grate bar is divided by the partition web 29.

The two air chambers of the grate bar are located respectively immediately over 10 and communicate with the central and side air chambers beneath the grate and into which the forced draft is delivered from the blower. It will be understood, of course, that reference is here made to only one side 15 of the furnace, as illustrated in Fig. 5. The passage 30 between the grate bar chambers is so disposed that it directs the air blast from the chamber 20, where it is highest in the grate to the chamber 13 and 20 takes the air from said chamber 13 and delivers the same to the first two twyer openings as indicated by the arrows. The purpose of this arrangement is to add slightly more pressure to the air delivered at this 25 region inasmuch as the combustion is substantially at a maximum in the fuel bed lying between the first five or six twyers on either side of the retort 11 (see Fig. 5).

Referring to the furnace construction 30 shown in Fig. 5, 6 designates a suitable fireplace constructed of fire brick, or other material, and on which the grate structure is erected. Said structure consists of suitable supports 7 on which the walls 8 and 9 are 35 mounted, the wall 9 dividing the grate structure in zones or compartments through which the forced draft is admitted and controlled by suitable sliding valve mechanisms 10 as shown.

40 The stoker mechanism consists of a retort 11 and a coal pusher 12, and for a more detailed description of these features of the furnace reference may be had to the co-pending application for U. S. Patent, 45 bearing the Serial No. 176,240, dated June 21, 1917, and on which construction the present arrangement is proposed as an improvement.

50 A plurality of grate bars 13 are mounted on the grate structure 8 and the side wall of the retort 11, and the alternate bars of the grate are adapted to be reciprocated through the operation of the stoker mechanism. The grate bars intermediate said 55 movable grate bars are stationary and secured in any approved manner, and the usual pair of dumping grates 14 (one being shown) are pivotally mounted at the opposite outer ends of the grate bars.

60 The means for operating the movable grate bars from the stoker mechanism consists of a rocker shaft 15 mounted to oscillate in the journal bearing 16 formed at the upper end of the retort wall 11, and said

shaft is constructed with a flange or web 65 portion 17 engaging within the notch 18 formed in the lower edges of the movable grate bars up on one side of the retort in such manner that said grate bars are reciprocated when the shaft oscillates.

70 The grate bar shown in Fig. 6 consists of a hollow structure formed on two similar parts and united along a longitudinal medial plane although it will be understood, of course, that the grate bar may be 75 made in one piece as shown on Fig. 9. Each grate bar is provided with a transverse web portion on baffle 19 that is disposed immediately over the partition 9 and flange portion 17 of the rocker shaft 15, and said web 19 with the flange 17 and partition 9 will form a virtually continuous partitioning wall or barrier that will divide the forced draft admitted into the fire place.

75 The forced draft entering the chamber 20 on one side of the web 19 in each grate bar issues through the ducts 21 provided at the inner end or head of the grate bar, and through these ducts the forced draft passes into the heaviest part of the fuel bed, i. e., directly above the retort 11. The dividing web on baffle 19 provides a duct or constricted passage 22 that enters into the air space between the walls 8 and 9 of the supporting structure, and by this 90 arrangement of the air will pass into the lower or outer portion of the grate bar. This provision will enable to be maintained the same static pressure in the retort zone as the initial pressure, but the small portion 95 of the air which passes beneath and around the dividing webs 10 of grate bars will allow a much lower static pressure to be maintained under the grate bars at those portions most distant from the retort. The 100 reason for this lower static pressure is due to the constricted passage 22 and it will be further noted that the converse to the foregoing is true. Thus air may be passed from the outer air spaces of the grate bars 110 into the inner spaces 20 thereof, all depending upon which of the controlling valves 10 is open or closed.

105 In the construction shown in Fig. 6 the grate bar embodies practically the same 115 features as disclosed by the grate bar in Fig. 5 with the exception that the web or baffle 23 is considerably shorter and does not have any appreciable deflecting effect on the air.

120 It is obvious that those skilled in the art may vary the details of construction and arrangement of parts without departing from the spirit of my invention, and therefore I do not wish to be limited to such features except as may be required by the claims.

125 Having thus described my invention what

I claim as new and desire to secure by Letters Patent is:

1. A grate for forced draft furnaces comprising a plurality of reciprocatably mounted grate bars, a partition dividing the supporting structure into separate air intake conduits, co-acting members carried by the bars forming a constricted passage by way of the bar structure between the conduits, and means to reciprocate the bars without interfering with the constricted passages.

2. A grate for forced draft furnaces comprising a plurality of reciprocatably mounted grate bars, a partition dividing the supporting structure into separate air intake conduits, co-acting members carried by the bars forming a constricted passage by way of the bar structures between the conduits, and a rocking section formed in the said partition and adapted to reciprocate the bars without interfering with the constricted passages.

3. A grate for forced draft furnaces comprising a plurality of reciprocatably mounted grate bars, a partition dividing the supporting structure into separate air intake conduits, co-acting members carried by the bars forming a constricted passage by way of the bar structure between the conduits, and means to reciprocate the bars without interfering with the constricted passages, said bars being provided with twyer openings in connection with the several conduits.

4. A grate for forced draft furnaces comprising a plurality of reciprocatably mounted grate bars, a partition dividing the supporting structure into separate intake conduits, co-acting members carried by the bars forming a constricted passage by way of the bar structures between the conduits, and means to reciprocate the bars without interfering with the constricted passages, said bars being provided with groups of twyer openings, each group in connection with different conduits.

5. A grate for forced draft furnaces comprising a plurality of reciprocatably mounted grate bars, a partition dividing the supporting structure into separate air intake conduits, co-acting members carried by the bars forming a constricted passage by way of the bar structure between the conduits, and a rocking section formed in said partition adapted to reciprocate the bars without interfering with the constricted passages, said bars being provided with groups of twyer openings, each group in communication with different conduits.

In witness whereof, I have hereunto set my hand and seal at Philadelphia, Pennsylvania this 8th day of October, A. D. nineteen hundred and seventeen.

JOSEPH H. ROACH. [L. S.]
